(57) **CLAIM**

The ornamental design for a mug as shown and described.

DESCRIPTION

FIG. 1 is a top, front, right perspective view of a mug showing our new design;

FIG. 2 is a rear view thereof;

FIG. 3 is a front view thereof;

FIG. 4 is a right side view thereof;

FIG. 5 is a left side view thereof;

FIG. 6 is a top view thereof;

FIG. 7 is a bottom view thereof;

FIG. 8 is a bottom, rear, left perspective view thereof;

FIG. 9 is a top, front, right perspective view of an alternative claimed configuration of the mug of FIGS. 1-9 showing our new design;

FIG. 10 is a rear view thereof;

FIG. 11 is a front view thereof;

FIG. 12 is a right side view thereof;

FIG. 13 is a left side view thereof;

FIG. 14 is a top view thereof;

FIG. 15 is a bottom view thereof; and,

FIG. 16 is a bottom, rear, left perspective view thereof.

The pairs of jagged broken lines are shown broken away to disclose indeterminate length, and the portions of the design that may be visible between such jagged lines have been removed for clarity. Neither the jagged broken lines nor portions of the design not visible between such jagged lines form any part of the claimed design. The broken lines within the shaded area show features that form no part of the claimed design. The broken lines depicting the remainder of the mug form no part of the claimed design.
